Geo. W. Smith, of Hartford, Conn.
Letters Patent No. 1096. Dated April 26, 1859.

The schedule referred to in these Letters Patent and making part of the same.

To all whom it may concern;

Be it known that I, G.W. Smith, of Hartford, in the County of Hartford and State of Connecticut, have produced a new and ornamental Design for Tea-pots, Coffee-pots and other articles of tea and coffee sets, and I do hereby declare that the following is a full, clear and exact description of the same, reference being had to the accompanying drawings making part of this Specification.

Figure 1. is a side elevation of a tea-pot formed after the improved design.

The distinguishing feature of this design consists in producing a series of configurations and embellishments which shall present a harmonious and beautiful appearance, when embodied in a tea or coffee-pot, and preserve these characteristics when modified to adoption to the ornamentation of the several articles of tea and coffee set.

The base A, of the tea-pot is formed somewhat sim-

ilar to the Scutia and upper half of the torus of the Composite order of Architecture, combined, and in order to accord with the flutes B, and convex ridges C, running into each other, and the imbraced quarter-fool and trefoil embellishments in which they terminate, it is ornamented at its lower part with a series of befool embossings D, which point to the centre at the upper portion, and run into each other below.

The Spout E, is fluted and ridged to correspond with the body of the pot, and its upper end, like the portions of the handle F, next the said body, is embellished with simple Crochet work, somewhat similar to the Embossing G, at the top of the pot, and of the same degree of finish as the Quarterfool and trefoil ornamentations at the top and lower ends of the flutes B, and ridges C.

The tea pot embellished as above is surmounted with a cover H, having convex ridges formed in it, which extend upward to the base of a crown piece I, formed somewhat similar to a pine apple, and ornamented with inverted leaves and such other elaborate Crochet work, as will afford a proper finish to the upper portion of the vessel and make it harmonize with the series of embellishments below.

The cima-reversa and cima-recta flutes and ridges, Configurations, and the several Embellishments described and represented in connection with a tea or coffee pot, are alike applicable to the various articles embraced in a tea or coffee set, and when such articles are adorned with these features, the same relative proportions are observed in order to preserve their beauty and harmony.

What I claim as new and desire to secure by Letters Patent, is, ^{Op. 1} For a living tea and coffee pots and other articles of tea and coffee sets, ^{Op. 2} the Configurations, flutings and ridges, Embossings, and other Adornments before described, so as to produce a simple, chaste and highly ornamental design.
